US00D512672S

(12) **United States Design Patent** (10) Patent No.: **US D512,672 S**
Yamazaki et al. (45) Date of Patent: **** Dec. 13, 2005**

(54) **INSTRUMENT CLUSTER CONFIGURATION**

(75) Inventors: **Yuichi Yamazaki**, Rancho Palos Verdes, CA (US); **Jamie Klopp**, Hermosa Beach, CA (US)

(73) Assignee: **Honda Motor Co., Ltd.**, Tokyo (JP)

(**) Term: **14 Years**

(21) Appl. No.: **29/219,860**

(22) Filed: **Dec. 23, 2004**

(51) LOC (6) Cl. **12-16**

(52) U.S. Cl. **D12/192**

(58) Field of Search **D12/192; 180/90; 280/750-752; 296/190-191, 70; D10/46; 102, 98, 122-127**

(57) **CLAIM**

The ornamental design for an instrument cluster configuration, as shown and described.

DESCRIPTION

The FIGURE is an elevational view of an instrument cluster configuration showing our new design.

The broken line showings of the indicia on the meters are for illustrative purposes only and form no part of the claimed invention.
